H. G. Manning
ATTORNEY

UNITED STATES PATENT OFFICE.

JAMES EMILE MORAN, OF WATERBURY, CONNECTICUT.

BEDSTEAD BOOK HOLDER.

Application filed July 21, 1925. Serial No. 45,013.

This invention relates to reading brackets, and more particularly to an adjustable bracket adapted for attachment to a bed for holding a book in an inverted position, so as 5 to be visible to a patient lying in said bed.

One object of this invention is to provide a device of the above nature which is adapted to be adjustably and detachably clamped to the horizontal rear bar of a bed.

10 A further object is to provide a reading bracket of the above nature adapted to be adjustably supported upon a bedstead in reading position, and which may be readily swung out of the way when not in use.

15 A further object is to provide a device of the above nature which will be simple in construction, inexpensive to manufacture, easy to install and manipulate, and very efficient and durable in use.

20 With these and other objects in view, there has been illustrated on the accompanying drawings, one form in which the invention may be conveniently embodied in practice.

Fig. 1 represents a side view of the reading 25 bracket showing its appearance when installed in reading position upon a bed.

Fig. 2 is an edge view of the base plate and supporting strip, and showing a book held in inverted position upon said base plate.

30 Fig. 3 is a top view of the reading bracket as it appears when supported upon a bedstead.

Fig. 4 is a perspective view of one jaw of the clamping member for holding the bracket upon the rear horizontal bar of a bedstead.

Referring now to the drawings in which like reference numerals denote corresponding parts throughout the several views, the numeral 10 indicates a flat base plate substantially rectangular in form and having rounded corners. The base plate 10 is adapted to support a book 11, said book being held in open position in any suitable manner, as by rubber bands 12, passing transversely and longitudinally about said plate.

45 In order to adjustably support the reading bracket, each end of the base plate 10 is provided with an angle member 13, said angle member being connected by bolts 14 and wing nuts 15 to a pair of slotted side strips

16. Each of the side strips 16 is provided at its upper end with a guiding strap 17 secured to the side strip 16 by a pair of bolts 18 and

19. The bolt 19 is provided with a washer 19^a and a wing nut 20, whereby the guiding

strap may be loosened to permit it to be slid along in the slot 21 of the side strip 16.

Each of the guiding straps 17 and the side strips 16 are adapted to slidably engage the side arms 22 of a U-shaped member 23, said 60 arms 22 extending rearwardly and being pivotally connected, as by bolts 24, to the front jaws 25 of a pair of clamping members. The front jaw 25 of each clamping member is in turn secured, as by a bolt 26, to the rear 65 jaw 27 of said clamping member. As clearly shown in Figs. 1 and 4, the jaws 25 and 27 are provided with cooperating curved fingers 27^a and 28 which are adapted to encircle the rear bar 28^a of a bedstead. 70

The front jaw 25 is provided with a set screw 29 which is adapted to be driven inwardly into contact with the bar 28^a in order to hold the clamping member from twisting about the bar. The front jaw 25 is also 75 provided with a shoulder 30 adapted to support the arms 22 of the U-shaped member 23 to maintain the bracket in reading position as long as may be desired.

It will be understood that when the patient 80 has finished his reading, the bracket 10 may be pushed up and moved out of the way merely by swinging the U-shaped member 23 rearwardly until the arms 22 come into contact with the front jaws 25.

It will also be understood that while the improved reading bracket is especially adapted for use in an inclined position for overhead reading by a patient lying on his back, the bracket may also be held vertically 90 or horizontally or in any other position. For example, the bracket may also be arranged to lie flat on the patient's lap so that the book may be read while he is in a sitting position.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit, in short, the invention includes all the modifications and embodiments coming within the scope of the following claims. 95

Having thus fully described the invention, what is claimed as new and for which it is desired to secure Letters Patent, is:

1. In a bedstead book holder, a base plate adapted to hold a book, means for supporting 110

said base plate in inverted position above the position of the pillow of a bed comprising a pair of side strips connected to the ends of said base plate, guide straps secured to said side strips, a U-shaped member upon which said side strips and said guide straps are slidably mounted, and means for clamping said U-shaped member to the rear of the bed.

2. In a bedstead book holder, a swinging U-shaped member, means for clamping the ends of the U-shaped member to the horizontal frame member of the head of a bedstead, a pair of depending strips at the forward extremity thereof, an inverted book supporting base secured to the lower ends of said depending strips, said U-shaped member being pivoted to said clamping means, whereby said bookholder may be swung out of the way when not in use, and said clamping means having a forward shoulder for holding said base in reading position above the head of the user.

3. In a reading bracket for attachment to a bedstead, a base plate adapted to hold a book, means for supporting said base plate in an inverted position above the position of a

pillow of a bed comprising a pair of side strips connected to the ends of said base plate, guide straps secured to said side strips, a U-shaped member upon which said side strips are slidably mounted, each arm of said U-shaped member having a clamping member pivotally connected thereto, each of said clamping members comprising a pair of jaws adapted to engage said bedstead, and means for locking said jaws in clamping position, one of the jaws of each clamping member having a shoulder in which the adjacent arm of the U-shaped member is adapted to seat when the bracket is lying in active position.

4. In a bedstead book holder, a swinging U-shaped member, a pair of book-supporting strips depending from the base of the U-shaped member, and a pair of clamps pivotally connected to the legs of said U-shaped member for adjustably securing said book holder in any desired position upon a bedstead.

In testimony whereof, I have affixed my signature to this specification.

JAMES EMILE MORAN
